UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

MACHINE FOR MAKING CAN-BODIES.

1,234,182.

Specification of Letters Patent. Patented July 24, 1917.

Application filed February 27, 1913. Serial No. 751,051.

To all whom it may concern:

Be it known that I, PETER KRUSE, a citizen of the United States, residing in the borough of Brooklyn, county of Kings, city 5 and State of New York, have invented certain new and useful Improvements in Machines for Making Can-Bodies, of which the following is a specification.

In the making of tin cans it is customary 10 to feed flat sheets of tin cut to the required size successively to apparatus which first bends up and down the opposite edges to form hooks; then to advance the sheet to a point where it is folded around an expanding mandrel called the "horn" in such manner that the hooked edges are interlocked, whereupon the horn expands and draws these hooks together, and a ram called the "bumper" then descends and squeezes the 15 interengaging hooks against the horn to form the side seam of the can. This ends the work peculiar to the so-called body-forming machine as heretofore usually constructed. The subsequent operations have 20 been performed by transferring the can bodies to other machines. These operations include the bottoming, to which the present invention has no reference. The operations performed at 25 the top of the can body vary according to the kind of can to be made. For cans which receive a slip cover, it is customary to true and contract or taper the upper end of the can body to fit it to the cover, this operation being called "necking." In some cases 30 the neck is reduced to perceptibly smaller size than the can body, this specific operation being called "necking in." In some cases a bead is formed between the neck and 35 the body, this operation being called "beading." In some cases the bead instead of being at the bottom of the neck is formed lower down. Heretofore the operations of necking or necking in and beading have been 40 performed in a separate machine or machines by means of suitable dies.

The present invention provides for performing these successive operations of body forming and necking (or necking in), and 45 also the beading operation if desired, all in the same machine, whereby any further handling of the stock is avoided, and the operations are quickened, cheapened, and generally facilitated.

According to the present invention the

horn of the can body-forming machine is prolonged or carries an extension, and means are provided for sliding the newly formed can body along onto the extension of the horn, and the necking or necking and beading mechanisms are applied to operate upon the can body in this advanced location. After their operation the can body is fed along beyond them and may then be dropped out of the machine or conducted thence to 60 any other desired mechanism.

For the necking or necking and beading operation, exterior dies or jaws are provided which move inwardly and pinch the neck portion of the can body against the horn 70 extension, which latter forms an anvil or internal former for shaping the neck.

For simply necking or necking in, the horn extension may be solid so as to serve simply as an anvil or former. For beading, 75 the neck portion of the horn extension is made segmental and expansible, and is provided with a circumferential rib coacting with a circumferential groove in the external necking jaws, so that after these jaws 80 have closed upon the can body, the expansion of the segmental portion of the horn extension serves to crimp the metal into such external groove and thereby form the bead. The segments of the horn extension thus 85 form beading dies. These dies are retracted and the outer jaws are caused to move apart before the next forward feeding movement to enable the necked and beaded can body to be stripped from the horn extension and delivered beyond the machine.

The accompanying drawings show machines embodying this invention.

Figure 1 is a vertical section of so much of a can body former as is necessary to an 95 understanding of the invention, and illustrating the addition thereto of the necking mechanism;

Fig. 2 is an end elevation of the machine showing particularly the necking mechanism;

Fig. 3 is a fragmentary vertical longitudinal section on a larger scale;

Fig. 4 is an end elevation of Fig. 3;

Fig. 5 is a side elevation showing a modified construction;

Fig. 6 is an end elevation thereof;

Fig. 7 is an enlarged detail of part of Fig. 2.

I will first describe the machine which 110

completely embodies the invention, namely, that adapted to perform both the necking and beading operations.

Referring first to the general figures, 5 Figs. 1 and 2, the machine has any suitable supporting frame A, preferably surmounted as usual by an arch A' which supports the horn B, through the medium of a slide A². The horn is extended beyond the body- 10 forming position to constitute the horn extension B'. The body-forming horn B is made expandable in any of the known ways. The body-forming machine comprises as usual means for feeding forward the sheets 15 or blanks to bring them successively to the hook-forming and body-bending positions; and also any usual hook-forming devices and body-bending means for wrapping the hooked blank around the horn. As these 20 latter mechanisms are well understood and form no part of my present invention, they are not shown. The feeding means comprises a longitudinally sliding bar or bars C deriving motion from a crank C' on the 25 driving shaft D, the motion being transmitted through a link a, lever b and link c to the sliding feed bar C. This feed bar is provided with the usual fingers or pawls d d for pushing forward the flat blanks, and then 30 after they are wrapped around the horn, for pushing forward the can bodies so as to feed them off from the horn onto the extension B' and eventually off from the latter to feed them out of the machine.

35 Above the horn is the usual bumper or swaging hammer E for closing the side seam. It is connected as usual to a vertically moving slide F, and is operated by the usual lever G which derives its motion from 40 a crank G' on a shaft D', the movement being transmitted through a pull-rod e as usual. Or any other way known in the art may be provided for closing the side seam.

45 It is well understood that in body-forming machines it is necessary that the horn be contracted at the time when the body blank is being wrapped around it, in order that the hooked edges of the blank may overlap and be brought into line, whereupon 50 by expanding the horn these edges are caused to inter-lock, being pulled out into close engagement, whereupon the bumper or hammer comes down and closes them together to form the side seam, after which 55 the horn is contracted to release the body. For thus expanding and contracting the horn it may be constructed in any known manner. The construction shown in Fig. 3 involves making the upper or anvil part B² 60 of the horn in a separate piece or saddle and interposing between the main or rigid part of the horn and this anvil part, an expander H, being a slide having inclined or wedge-like faces engaging similar faces on 65 the under side of the anvil part, so that

when this slide is moved in one direction the anvil is lowered to contract the horn, and when moved in the contrary direction it is raised to expand the horn. The construction here shown is similar to that set forth 70 in my pending application Serial No. 709,227, filed July 13, 1912. Springs f are provided for drawing down the anvil part. For expanding the horn the expander slide H is moved endwise by the action of the 75 slide F, which has an incline g coacting with an incline g' on an extension of the slide H, a spring h being provided for restoring the expander. Thus the descent of the slide F first draws back the expander 80 slide H and expands the horn, and immediately thereafter it forces the hammer E against the side seam to close it.

The horn extension B' projects far enough to receive the can body when advanced one feeding movement (or it may be two feeding movements) beyond the body-forming position. At its end it is shaped to form the necking mandrel I, that is to say it conforms to the interior contour of the finished neck. If a bead is desired, a beading rib J is provided around the exterior. For necking or necking-in alone (see Fig. 5) the necking mandrel I may be formed integrally with the extension B' because no relative 95 movement is required. But for beading, the rib J must be formed on a part which is expandable, so that it may be contracted to bring this rib within the inner contour of the can body during the feeding movement 100 which brings the body into the necking and beading position, after which the rib bearing part may be expanded. In Figs. 3 and 4 the rib J and necking surface are shown as formed upon expanding dies or segments K, 105 of which four are shown. For mounting these they are provided with inactive portions which enter deeply within a recess L within the extension B', and to keep them in place screw pins i i are provided which enter the respective segments. For expanding the segments a special wedge M is provided having as many inclined faces as there are segments, each face conforming to the inner 110 face of its respective segment, so that an endwise movement of the wedge M in one direction expands the segments to project the beading ribs J, and its opposite endwise movement releases the segments and permits them to collapse or move inwardly to 115 retract the ribs. For imparting these movements to the wedge M it is convenient to provide a rod N, preferably formed integrally with the expander H, being prolonged through the extension B' and having the 120 wedge M fixed on its outer end. Hence the means for moving the expander H is made available for also moving the wedge or expander M, whereby the horn and the die segments K K are expanded simultaneously. 125 130

Outside of the horn extension B' and coincident with its necking end, are the necking jaws or dies P P. These are shown as four in number, although a greater or less 5 number of segmental jaws may be used. They are movable outwardly and inwardly in preferably simultaneous manner. They are shown as movable in straight radial paths, but this is not necessary. The preferable 10 construction is that shown, where these jaws or dies P P are carried on radially movable slides P' P', best shown in Fig. 2. They are shown as supported in an auxiliary frame Q adjustable relatively to 15 the main frame. For imparting the simultaneous inward or outward movements, they are acted upon by an oscillatory cam R shown in the form of a ring and having cam inclines *j* acting against rollers *k* on the respective slides. The ring R is oscillated in proper synchronism with the other 20 movements by means of a crank or equivalent means carried on the shaft D, the movement being conveniently taken from the 25 crank C' through the lever *b*, and thence through a rod *n*, an elbow-lever *o*, and a rod *p*. To introduce a certain cushioning or 30 yielding function whereby the necking jaws may approach more or less according to 35 variations in the thickness of the sheet metal, (and to afford a dwell in case the movement is taken from a crank), a cushioning spring *q* is interposed at any convenient point, preferably between sections of the 40 link *p*. The normal movement may thus be somewhat in excess of that which would close the jaws, this excess being taken up by the yielding of the spring. The specific construction shown will be best apparent 45 from the detail, Fig. 7, where the link *p* divided into two parts, has on one of them a sleeve *p'* against which the spring presses, and which has a slot *r'* in which moves a pin *r* on the other section of the link. The 50 spring is confined between the sleeve *p'* and a sleeve *p*², either or both being adjustable. The adjustment of the sleeve *p'* varies the length of the link as a whole; the adjustment of the sleeve *p*² varies the stress of the 55 spring. During the necking stroke an upward thrust is communicated to oscillate the ring and close together the jaws, and if these seat themselves and stop before the impelling movement ceases, the spring *q* takes up the excess of movement, the pin *r* sliding 60 up in the slot *r'*. During the opposite or opening stroke, the first movement reseats the pin *r* in the end of the slot, so that a positive opening movement is communicated 65 to the ring R. The opening movement of the jaws P P may be accomplished by means of appropriate cam faces or inclines on the ring R, or it may be performed by retracting springs, the latter being suitable. One of these springs is shown

at *s* in Fig. 2 as applied to one of the slides P'.

The body-forming elements perform in the well known manner. The body is then advanced by the next reciprocation of the feed slide to the necking position. The necking jaws P P then close upon the neck portion of the body. In so doing they may more or less contract the neck, conforming it to the necking mandrel I if the latter is stationary. In case the beading dies are used, the necking jaws close in upon the work in advance of the expansion of the segments K, so that as these segments expand the beading rib J is forced out to indent the sheet metal into the corresponding groove formed in the necking jaws P. These jaws then move apart and the wedge M moves to release the segments K, whereupon the can body is again advanced by the feeding mechanism to deliver it beyond the necking device, and either to discharge it from the machine or to advance to any other desired subsequently acting mechanisms.

Figs. 5 and 6 show the machine as modified for performing the operation of necking or necking in, without any beading operation. For this the necking surface or mandrel I is formed as a solid part of the horn extension B'. For simple necking the part I will be of nearly the same size as the horn extension B', so that the neck will not be materially reduced, while for necking-in if a smaller neck is to be formed, it will be of correspondingly smaller size. In the latter case the shoulder *t* forms the limiting shoulder at the bottom of the neck, there being a corresponding shoulder *t'* formed within the active faces of the necking jaws.

The machine is adaptable either to cylindrical can bodies or to those of a variety of other shapes. As two examples of such shapes, an oblong body is shown in Fig. 6 and an elliptical body in Fig. 4. The shape and number of jaws P P and of segments K K may be governed by the shape of the can body to be operated on.

It is desirable to make the machine adjustable to different sizes of can bodies, so that by simply removing the horn with its integral horn extension, and removing also the folders of the body forming mechanism and the jaws P P, and by substituting a horn, folders, and jaws of a different shape, a different can body may be formed and necked. After such substitution, if the size of the can body is thereby altered, the necking mechanism may require to be adjusted up or down to recenter it with the horn, or to be adjusted longitudinally of the horn to bring the necking jaws into coincidence with the plane of the neck to be formed. To permit of these adjustments the frame Q is carried upon a yoke Q', which latter is vertically adjustable upon the main frame A, 120 125 130

while the frame Q is longitudinally adjustable upon the yoke. To vertically adjust the yoke Q' its fastening screws *u* are slackened and an adjusting screw S is turned by its hand wheel to raise or lower the yoke, after which the screws *u* are retightened. The frame Q is mounted upon the yoke in longitudinal dovetailed slideways *v*, and is adjusted by the turning of a screw T by means of its hand wheel. For adjusting the cam ring R and thereby setting the slides P' P' out or in, the extensible link *p* may be adjusted by its screw sleeve *p'*, or the effective length of the link *n* may be altered by means of the adjusting nuts shown at *m m* which govern its point of connection with the lever *b*. Any other suitable adjustments may be provided as desired.

Part of the mechanism of the machine herein set forth is similar to that disclosed in my application Serial No. 708,545 filed July 10, 1912, for a machine for beading and flanging can bodies.

The mechanism herein illustrated may be considerably varied or modified without departing from the essential features of my invention which are set forth in the claims hereunto appended.

I claim as my invention:—

1. The combination with can body forming mechanism comprising an expanding horn, of necking and beading mechanism comprising an extension of said horn, exterior jaws movable inwardly to embrace the neck portion of the body, and internal seg-

ments movable outwardly to squeeze the metal against said jaws, an expander within said segments, and expansion mechanism for said horn connected to operate said expander.

2. The combination with can body forming mechanism comprising an expanding horn, of necking and beading mechanism comprising an extension of said horn, exterior jaws movable inwardly to embrace the neck portion of the body, and internal segments movable outwardly to squeeze the metal against said jaws, a horn expander movable longitudinally of the horn, and an expander for said segments connected to said horn expander to move coincidentally therewith.

3. The combination with can body forming mechanism comprising an expanding horn, of necking and beading mechanism comprising an extension of said horn, exterior jaws movable inwardly to embrace the neck portion of the body, and internal segments movable outwardly to squeeze the metal against said jaws, and expanding mechanism adapted to simultaneously expand the horn and impart such outward movement to said segments.

In witness whereof, I have hereunto signed my name in the presence of two subscribing witnesses.

PETER KRUSE.

Witnesses:

E. A. MAIN,
C. T. ZIEGLER.

DISCLAIMER

1,234,182.—*Peter Kruse*, Brooklyn, N. Y. MACHINE FOR MAKING CAN-BODIES.
Patent dated July 24, 1917. Disclaimer filed April 1, 1929, by the assignee by
mesne assignments, *E. W. Bliss Company*.

Therefore disclaims any subject matter which may be included within each or any of claims 1, 2 and 3 of said patent, except when the horn-expanding device and the expanding device for the internal segments are operated from the body-forming end of the horn, so that their operative connections do not interfere with the feeding of the longitudinally-separated can body sheet at the body-forming end of the horn, and so that the necessity of moving any such operative connections away from the discharge end of the horn to remove the can, is avoided.

[Official Gazette April 16, 1929.]
